United States Patent Office

Des. 202,768
Patented Nov. 9, 1965

202,768

VACUUM CLEANER

Charles J. Davis, Philadelphia, and Harper Landell, Fort Washington, Pa., and William W. Chambers, Towson, Md., assignors to The Black and Decker Manufacturing Company, Towson, Md., a corporation of Maryland

Filed Nov. 20, 1964, Ser. No. 82,714

Term of patent 14 years

(Cl. D9—2)

FIG. 1

FIG. 6

FIG. 7

FIGURE 1 is a perspective view of a vacuum cleaner showing our new design;

FIGURE 2 is a front elevation thereof;

FIGURE 3 is a right side elevation;

FIGURE 4 is a left side elevation;

FIGURE 5 is a top view;

FIGURE 6 is a rear view; and

FIGURE 7 is a bottom view.

The broken lines shown in FIGURE 3 are for illustrative purposes only.

We claim:

The ornamental design for a vacuum cleaner, as shown and described.
